COMBINED ASH TRAY AND MEMORANDUM
HOLDER

Anton G. Hanson, Minneapolis, Minn.

Application August 14, 1948, Serial No. 148,113

Term of patent 7 years

(Cl. D85—2)

To all whom it may concern:

Be it known, that I, Anton G. Hanson, a citizen of the United States, residing at Minneapolis, in the county of Hennepin and State of Minnesota, have invented a new, original, and ornamental Design for a Combined Ash Tray and Memorandum Holder, of which the following is a description, reference being had to the accompanying drawing, forming part thereof.

Figure 1 is a perspective view of a combined ash tray and memorandum holder, showing my new design;

Figure 2 is a plan view thereof; and

Figure 3 is a side elevational view thereof.

I claim:

The ornamental design for a combined ash tray and memorandum holder, as shown.

ANTON G. HANSON.
